UNITED STATES PATENT OFFICE.

ANTHONY FRICKER, OF CLEVELAND, OHIO.

BITUMINOUS DISTRIBUTER.

1,297,136.

Specification of Letters Patent. Patented Mar. 11, 1919.

Application filed September 27, 1917. Serial No. 193,447.

REISSUED.

To all whom it may concern:

Be it known that I, ANTHONY FRICKER, a citizen of the United States, and resident of Cleveland, in the county of Cuyahoga and State of Ohio, have invented new and useful Improvements in Bituminous Distributers, of which the following is a description, reference being had to the accompanying drawings, which are a part of this specification.

The invention relates to machines for distributing bituminous material, such as asphalt and petroleum products for road making.

15 The invention is more particularly designed to provide mechanism for controlling the pressure upon the material in the discharge manifold by means of a valve in a by-pass leading back to the source of supply and also for insuring the efficient heating of the manifold by the circulation of material through it.

The invention further consists in the several features hereinafter set forth.

25 In the drawings:

Figure 1 is a view of the device embodying the invention shown in connection with the storage or supply tank;

Fig. 2 is a section taken on the line 2—2 of Fig. 1;

Fig. 3 is a section taken on the line 3—3 of Fig. 1.

In the drawings, the numeral 4 represents the supply tank for the bituminous material. Owing to the character of this material it has to be heated by heaters (not shown) but which are well understood by persons skilled in this art.

40 The material from the tank 4 passes through a pipe 5 to a pump 6, of any suitable construction, from which it is delivered through a pipe 7 into the central portion of what is termed the manifold 8. This manifold is provided with a plurality of discharge nozzles 9, through which the material is discharged onto the road through the operation of suitable valves (not shown), one form of valve being shown in my copending application Serial No. 50 173,255, filed June 6, 1917.

In applying the material of this kind it is necessary to keep the manifold heated and also to control the delivery pressure from the manifold to suit different requirements of the work to deliver more or less material in a given period through the

nozzle 9. To accomplish this purpose I have provided a by-pass pipe 10 having branches 11 leading to the ends 12 of the manifold and connected at its upper end 13 60 to the tank 4. With this construction it will be apparent that some of the material delivered by the pump 6 will flow under pressure from the pipe 7 into the manifold and through it into the branches 11 of the 65 by-pass pipe 10 and thence back to the supply tank 4 and that there will therefore be a constant circulation of heated material through the manifold to heat the same and prevent any tendency of the material, 70 which readily congeals under ordinary temperatures, from clogging the manifold.

To regulate the pressure by which the material is delivered from the manifold and consequently the quantity delivered through 75 the nozzles 9 in any given period I have provided a valve in the by-pass 10 which may be set by the operator to suit the conditions of the work.

This valve consists of a conical valve member 14 adapted to seat on a conical seat 15 formed in the by-pass pipe and provided with a stem 16 vertically slidably movable in guides 17 in the interior of the pipe. The member 14 is provided with holes 14' to 80 allow material in the by-pass to drain back into the manifold and prevent clogging of the valve. The means for setting this valve comprise a lever 18 having a slot 19 at one end in which a pin 20 secured to the stem 16 90 is mounted and having a ball shaped portion 21 intermediate its ends seated in a ball casting 22 formed in the pipe 10 and a member 23 so that the lever 18 may be swung vertically to open and close the valve. The 95 lever 18 also has a curved portion 24 provided with teeth 25 on its under side which are adapted to be engaged by a setting member 26 having teeth 27 and a pointer 28 and slidably mounted on the free end of a rod 29 100 pivoted at its lower end to the pipe 10, the member 26 being held in engagement with the lever 18 by a coiled spring 30 mounted on the rod and bearing upon the member 26 to press its teeth 27 into engagement with 105 the teeth 25 on the lever 18. The portion 24 of the lever is provided with a scale 31 representing pressures. With this construction when the member 26 is set so the pointer 28 registers with the scale designation "5" a 110 pressure of five pounds per square inch will be maintained in the pipe 10 and the valve

will be opened a predetermined distance while the pressure in the manifold will be such as to force the material through the nozzles 9 at best efficiency. As the member 5 26 is moved so as to bring the pointer 28 from the designation "5" to the designation "20" the valve is opened to a greater extent and the pressure in the by-pass pipe 19 increased while the pressure in the manifold is 10 decreased with a resulting decrease in the rate of flow of material from the nozzles 9. Thus the valve serves to control the pressure of the material in the manifold by decreasing the pressure in the by-pass pipe 19. 15 However, under working conditions the valve is always open to a greater or less extent, as desired, so that some material will flow through the manifold and return to the tank and thus keep the manifold heated 20 so that the material will not clog the nozzles 9.

The invention thus exemplifies a device for controlling the pressure upon the material in the manifold to regulate the discharge and for insuring efficient heating of 25 the manifold by the circulation of material through it.

I am aware that the details of construction herein shown and described are subject 30 to some modification and change but such changes as come within the scope of the appended claims I deem to be within the spirit of my invention.

What I claim as my invention is:

35 1. In a bituminous distributer, the combination, with the supply tank thereof, of a

discharge manifold provided with outlets, piping connecting said tank with the central portion of the manifold, and a by-pass pipe communicating with the supply tank and 40 having branches leading to the ends of the manifold.

2. In a bituminous distributer, the combination with the supply tank thereof, of a discharge manifold, means for introducing 45 material from the tank into the intermediate portion of the manifold and for conducting the material from the ends of the manifold back to the supply tank.

3. In a bituminous distributer, the combination, with the supply tank thereof, of a discharge manifold provided with outlets, piping connecting said manifold with said tank including a pump for delivering material from the tank to the manifold under 55 pressure, a by-pass leading from the manifold to the tank, and a valve in the by-pass for regulating the pressure of the material within the manifold, said valve having drainage openings therein. 60

4. In a bituminous distributer, the combination, with the supply tank, of a discharge manifold provided with outlets, means for delivering the material from the tank to the manifold under pressure, a by-pass leading 65 from the manifold to the tank, a valve in said by-pass for regulating the pressure of the material within the manifold, and means for permitting drainage of the material from the valve. 70

In testimony whereof, I affix my signature.
ANTHONY FRICKER.
